The ornamental design for a fan blade, as shown and described.

DESCRIPTION

FIG. 1 is a bottom perspective view of a fan blade showing our new design in use;

FIG. 2 is a top perspective view of the fan blade of FIG. 1; FIG. 3 is a front side elevational view of the fan blade of FIG. 1;

FIG. 4 is a rear side elevational view of the fan blade of FIG. 1;

FIG. 5 is a left side elevational view of the fan blade of FIG. 1;

FIG. 6 is a right side elevational view of the fan blade of FIG. 1;

FIG. 7 is a top plan view of the fan blade of FIG. 1; and, FIG. 8 is a bottom plan view of the fan blade of FIG. 1.

The broken lines shown in the drawings illustrate portions of the fan blade and environmental structure that form no part of the claimed design. The dash-dot-dash broken lines define the bounds of the claimed design and form no part thereof.
